UNITED STATES PATENT OFFICE.

THEODORE W. MUCKLE, OF DENVER, COLORADO, ASSIGNOR TO THE CASE MANUFACTURING CORPORATION, OF DENVER, COLORADO, A CORPORATION OF COLORADO.

MELTING-FURNACE.

1,286,719.

Specification of Letters Patent.

Patented Dec. 3, 1918.

Application filed March 18, 1918. Serial No. 223,096.

To all whom it may concern:

Be it known that I, THEODORE W. MUCKLE, a citizen of the United States, residing in the city and county of Denver and State of Colorado, have invented certain new and useful Improvements in Melting-Furnaces; and I do hereby declare the following to be a full, clear, and exact description of the invention, such as will others skilled in the art 10 to which it appertains to make, use, and carry out the same.

This invention relates to improvements in melting furnaces for reducing the contents thereof to a molten state with exceeding rapidity and without oxidation occurring.

It is true that furnaces have heretofore been in use, employing inserted crucibles or like containers, wherein the heat applied to the metal to be melted is an indirect or a 20 radiated heat, which will not, to any great extent, cause vaporization and oxidation of its volatile constituents, resulting in an oxidized scale-like scum or slag.

Manifestly, however, there are many objections to the use of crucibles, especially where the melting point of the metallic mass is 2000° F. or higher, or where the operations are to be carried out on a large scale; but for the present purpose of pointing out 30 emphatically the great utility of my invention, it will suffice to simply mention the two primary drawbacks of the breakage of the large expensive crucibles and the length of time requisite to thoroughly melt their contents, each of which in itself is a costly waste in point of direct actual expense and great loss of time, both in melting the mass and in replacing cracked or broken crucibles.

In consequence means have been diligently 40 sought for, whereby a naked blast flame and its hot gases might be utilized for positively directing an intense heat into intimate contact with the metallic mass, avoiding the use of crucibles entirely; but heretofore such 45 means have not been satisfactorily demonstrated or deemed wholly practicable, for the reason that when a blast flame strikes the metallic mass oxidation will occur, and in practice an oxidized scale or slaggy scum 50 has been known to flow off of the molten mass, almost as a stream, where there is an escape therefor, which results in a total loss of a large quantity of the desired reduced metal for casting purposes, or for pouring

into molds to be used later in other relations. 55 On the other hand, if this dross or slag is not run off or skimmed off of the surface of the molten mass, it interferes greatly with the direct rapid heating of the body of the mass itself.

However, if complete combustion has taken place, oxidation will not occur, regardless of the intensity of the blast flame, and its resultant hot gases caused to impinge directly upon the metallic mass, either 60 before or after melting has been substantially started or practically completed.

In carrying out my present invention, I take cognizance of this latter principle by the construction of a novel type of furnace, 70 whereby a highly intensified naked blast flame, after conversion into its resultant hot gases, is caused to swirl therearound in such manner that the hot gases travel in a spiral sheet-like path from the rear to the forward 75 pouring end thereof, with the top and side walls of the furnace confining and directing the initial flame and its hot gases, after complete combustion has taken place, across the metallic mass itself, the said mass, whether 80 partly or wholly molten, serving eventually as a bottom confining liquid wall or body surface for the blast, manifestly providing for a more direct and intimate heating of the molecular particles of said mass, but 85 without causing the oxidation thereof.

Another feature is to produce an improved furnace, for carrying out the foregoing principle, which is not only simple in construction and operation, but is also durable, efficient in action, and comparatively 90 inexpensive to manufacture and repair.

As other objects and advantages will fully appear, as incidental to the following disclosure, it would only be unnecessary repetition to further state them initially, but to 95 more clearly understand the details of the invention the improved furnace itself will first be described, after which the functioning of same will be more effectively apparent.

To this end, reference is directed to the accompanying drawings, in which Figure 1, is a longitudinal vertical sectional view taken, through the body of the furnace, in 105 the plane of the line 1—1 of Fig. 2; and Fig. 2, is a transverse vertical sectional view thereof, substantially along the line 2—2 of

Fig. 1, the supporting framework and exterior coöperating elements being shown in front elevation.

Before describing the furnace body proper, I will first refer to its supporting means and associated external parts, as these are less material in detail and may be conveniently combined in any suitable way to provide a compactly arranged portable structure.

In the drawings this arrangement is shown as comprising a light skeleton iron framework 5, upon which the furnace body is tiltingly mounted by the solid trunnion 6 and hollow trunnion 7, which latter is in communication with a rotary blower 8, preferably of the low pressure type, through the air conduit pipe 9, and is driven by any suitable form of motor, designated at 10 as an electric motor.

The outer end of the hollow trunnion 7 is preferably of reduced diameter, to be journaled in the framework, and is mounted in rotatable connection with the inturned 25 or upper elbow end of the air conduit pipe 9. This reduced end carries a worm gear wheel 11, meshing with a worm element (not appearing) on the shaft 12, operated by a hand wheel 13, for turning the furnace body on its trunnions, as will be selfevident.

14 is a branch air pipe leading from the hollow trunnion 7, and at its upper end supporting and opening into a suitable burner 15, preferably of the low pressure 30 type also, for supplying the necessary air under pressure thereto.

The nozzle of the burner in turn discharges, through a burner boss 16 secured to the furnace body, into and through the 40 fuel inlet opening 17, disposed tangentially of the upper curved interior wall thereof, which inlet opening is preferably of conical formation, with its delivery end flaring inwardly to spread out the blast flame upon 45 ignition as it enters the melting chamber.

18 is a fuel oil or gas inlet pipe for the burner, and 19 indicates a damper arrangement for regulating the supply of air under pressure through the branch air pipe 14, 50 while 20 designates the usual needle valve for controlling the admission of oil or gas, as is well understood.

The melting chamber 21 is of a peculiar contour, for certain purposes as will herein- 55 after appear, and it is walled by a thickened refractory lining 22 of fire clay or its equivalent, set up as a replaceable whole or in sections as desired, and between which and an outer iron incasing sheathing 23 there 60 may be interposed a heat resisting filling 24, such as asbestos or the like. The rear iron wall plate 25 may be flat and the front wall incased in a conical iron shell 26, both of which are detachably assembled to permit 65 of the ready removal and replacing of the re-

fractory lining when required, the whole outer casing being bound together around the furnace box by suitably arranged tie-rod connections.

The top wall of the furnace is apertured 70 to provide a feed inlet opening 27 for the metal to be melted, while the front wall is also apertured to provide a pouring outlet, which also serves as an exit for exhausting the spent gases.

The feed opening 27 is provided with any suitable form of closure, shown as a recessed seating plug 29 of refractory material, having lifting means or handles 30 and laterally projecting pins 31, the latter being adapted to interlockingly coöperate with oppositely disposed hooked pins 32, for releasing and locking the closure plug by a slight rotation of the same.

It will be noted that the inner face 33 85 of the top wall of the melting chamber is of arched, or semi-cylindrical, lateral curvature to approximately the position of the pouring outlet 28, but the inner face 34 of the bottom wall terminates short of the 90 radius of said arch and is flat surfaced, while the front wall is conically shaped to provide a retarding reverberative surface 35. Also the inner flaring upper surface of the fuel inlet opening 17 is substantially in 95 tangential line with the curved top surface 33 of the melting chamber. Most of these features I deem to be of material importance, in the functioning of my improved furnace as will presently appear, and I desire, 100 therefore, to emphasize the same at this point, before proceeding with an exact statement of operation itself, which now will have been fairly apparent and may be briefly set forth as follows.

At first a suitably proportionate charge of the metal to be melted, scrap or otherwise, is introduced through the feed opening 27, and as it becomes partially melted, after the furnace gets fairly started, additional 110 charges are added, so that the molten or partially molten mass rises in the bottom of the melting chamber until an approximate desired level is reached, indicated at the dotted line 37 just below the bottom of the 115 pouring outlet 28 to prevent any splashing or slopping out therethrough from the impact of the blast, which is directed through the fuel inlet 17 with powerful force, and is immediately ignited with a resultant highly 120 intensive degree of heat.

This blast flame and its entrained hot gases spread out in a sheet-like form as they are deflected around the curved surface 33 125 downwardly toward and across the liquid surface line, in the direction as indicated by the arrows *a*, which liquid surface comprises the bottom confining boundary thereof; but before the flame and hot gases have reached the semi-molten mass complete combustion 130

has taken place, and with the presence of oxygen removed, the oxidation of any metallic values is also eliminated.

As the blast of hot gases strikes this liquid surface the latter becomes agitated or riffled to some considerable extent thereby, causing a constantly changing molecular surface, and hence a more intimate heating of the particles thereof, thus greatly accelerating the melting operation; but even outside of this feature, the bottom of the melting chamber being a flat surface, instead of curved concavely, the depth of the molten mass will be uniform in any vertical plane transversely cutting the same. Consequently the heating of the bodily mass is proportionately uniform, which would not be the case with a concave bottom surface. This will be equally true, whether the furnace body is in a direct horizontal position, as shown, or slightly tilted upwardly at its pouring end, although in the latter instance the depth of the mass will not be uniform relatively to a vertical longitudinal plane cutting the same, as the depth at the rear will be slightly greater than toward the front, but for all practical purposes this will be compensated for and the heating of the bodily mass will be commensurately uniform, as the entering blast, at its highest degree of intensity, will first act on the thicker portion, in its spirally advancing path to the outlet end of the furnace, and as indicated by the upwardly directed and forwardly curving arrows *b*, while the retarding reverberative surface 35 will aid in equalizing, to a substantial degree, the heat at the forward end of the furnace, as will further appear.

From the foregoing, therefore, it will be seen that the sheet-like blast of hot gases, resulting from the naked blast flame after complete combustion has taken place, is caused to traverse the length of the furnace, in a swirling spirally advancing path across the whole exposed surface of the melting mass and with a non-oxidizable direct heating action, until striking the forward conical deflecting wall 35, when partial rearward reverberation results before final expulsion of the then almost spent gases through the outlet 28, thus additionally maintaining the full intensity of the heat within the furnace at its forward end.

Melting may be continued as long as necessary, and after total melting, the operation of pouring will be apparent, without further description, the furnace being of the tilting type, rotatably mounted on its trunnions as heretofore described, for facilitating this pouring.

In actual operations I have made complete successive meltings, with little or no waste resulting from the formation of an oxidized slag-like scum, and in an incomparably short

space of time, relatively to methods heretofore employed.

Finally I do not limit myself to the exact steps and details of the invention as specifically disclosed, excepting as they fall within the purview of the ensuing claims, when construed in the light of the specification, contemplating a fair range of equivalents; but what I do claim, as new and patentable, is:—

1. A potless melting furnace, adapted to be disposed in substantial horizontal position, having a melting chamber with a flat surfaced bottom, and being provided with a fuel inlet toward the top rear end thereof and an outlet toward the opposite forward end, in combination with means for introducing a fuel mixture, directed through said inlet, in the form of a strong blast flame projected across the top of said chamber and down its opposite side wall, for permitting of its substantial complete combustion before striking the melting mass on its flat surfaced bottom, the whole functioning for the purposes and in the manner, substantially as described.

2. A potless melting furnace, adapted to be disposed in substantial horizontal position, having a melting chamber provided with a front outwardly projecting inclined wall, a fuel inlet toward the top rear end of said chamber, and an outlet through said front wall, the interior face of which latter serves as a reverberating surface, in combination with means for introducing a fuel mixture, directed through said inlet, in the form of a strong blast flame projected across the top of said chamber and down its opposite side wall, for permitting of its substantial complete combustion before striking the melting mass, and the whole functioning for the purposes and in the manner, substantially as described.

3. The combination with a main support, of a potless melting furnace tiltingly mounted thereon to swing from a substantially horizontal position, the said furnace including a melting chamber having a flat surfaced bottom wall and a projecting conical front reverberating wall; a fuel inlet opening entering said chamber tangentially of its rear top wall; an outlet through said conical front wall; a burner associated with said inlet opening and having a fuel feed inlet and an air intake; a blower; means for operating the latter; an air conduit pipe leading from said blower to the air intake of said burner; and means for tilting said furnace, the several elements and the whole arrangement functioning for the purposes and in the manner, substantially as described.

4. The combination with a main support, of a potless melting furnace tiltingly trunnioned thereon to swing from a substantially horizontal position, and one of its trunnions

1
being hollow, the said furnace including a melting chamber having a transversely arched top wall, a flat surfaced bottom wall, and a projecting conical front reverberating wall; a fuel inlet opening entering said chamber tangentially of its rear arched top wall; a blower; means for operating the latter; an air conduit pipe leading from said blower to said hollow trunnion; a branch

10 air pipe leading from said hollow trunnion;

a fuel burner carried by said branch pipe, and communicating therewith, in fixed alignment with said inlet opening, the said burner having a fuel feed inlet; and means for tilting said furnace, through its trunnioning supports, the several elements and the whole arrangement functioning for the purposes and in the manner, substantially as described. 15

In testimony whereof, I affix my signature.

THEODORE W. MUCKLE.
